PORATION OF PENNSYLVANIA.

COOLING SYSTEM.

1,159,910.

Specification of Letters Patent.

Patented Nov. 9, 1915.

Application filed July 13, 1914. Serial No. 850,727.

To all whom it may concern:

Be it known that we, GEORGE M. EATON and SIDNEY W. FARNSWORTH, citizens of the United States, and residents of Pittsburgh, 5 in the county of Allegheny and State of Pennsylvania, have invented a new and useful Improvement in Cooling Systems, of which the following is a specification.

Our invention relates to a cooling system: 10 for vapor rectifiers, X-ray tubes, and other types of vacuum electric apparatus, and it has for its object to provide means whereby certain parts of the apparatus may be maintained at a predetermined difference of temperature from certain other parts of the apparatus and whereby such predetermined temperature difference may be readily adjusted.

Referring to the accompanying drawing, 20 Figure 1 is a view, partially in section and partially in elevation, of a vapor rectifier embodying our invention; Fig. 2 is a view, partially in section and partially in elevation, of a modification of our invention as 25 applied to a vapor rectifier; and Fig. 3 is an enlarged view, in section, of the anode shown in Fig. 1.

In the operation of vapor rectifiers and like apparatus, it is essential to satisfactory 30 operation that the temperature of the electrodes be kept within reasonable limits and that the relative temperatures of different electrodes be capable of definite control. The cooling of vapor rectifiers of large sizes 35 is generally accomplished by circulating water and, since it is desirable to maintain the anodes of such devices at a higher temperature than the cathodes, it is customary to pass the circulating water through the 40 cathode-cooling space prior to passing it through the anode-cooling space. With different loads and voltages, it is essential that the ratio of the anode temperature to the cathode temperature be altered, and our 45 invention provides an effective means whereby this result may be attained.

Referring to the form of our invention shown in Figs. 1 and 3, 4 is a containing receptacle of any desired material, such as 50 sheet steel, provided with a tight cover 5. An anode 6 projects through the cover 5, and is insulated therefrom by any suitable gas-tight joint 7 and is supplied with current by a conductor 8. A pool of mercury 9

in the bottom of the container 4 acts as the 55 cathode, and current is supplied thereto by a conductor 10 clamped directly to the cover. The cathode is maintained in activity by any suitable means, such, for example, as a keep-alive circuit indicated at 11. A casing 12 surrounds the container 4 and is spaced therefrom to provide a cooling jacket 13. The anode 6 is hollow, and a tube 14 projects thereinto nearly to the lower end thereof. An annular sleeve 15 surrounds the 60 lower end of the tube 14 and extends to a point adjacent the end of the anode. A rod 16 is provided whereby the sleeve 15 may be raised and lowered as desired. Cooling 65 fluid is supplied to the space 13 by a pipe 17 and flows therefrom through a pipe 18 of rubber or other insulating material and downwardly through the pipe 14. At the 70 lower end of the pipe 14, the current of fluid is divided, a portion passing downwardly and under the edge of the sleeve 15, as indicated by arrows 19, and a portion flowing upwardly and out through the neck of the anode, as indicated by arrows 20. The relative amounts of fluid flowing 75 in each of these two paths may be adjusted by raising and lowering the sleeve 15. The flow indicated by the arrows 19 cools the 80 active portions of the anode, and this stream then unites with that indicated by the arrows 20, passing upwardly through the annular space between the tube 14 and the neck of the anode and passing off through a pipe 21 provided with a suitable insulating joint 22. The cathode will be main- 85 tained at a lower temperature than the anode, since the cooling fluid impinges thereupon when at its lowest temperature, and the anode may be maintained at a predeter- 90 mined temperature above the cathode by 95 means of the sleeve 15. By lowering the sleeve 15, the supply of cooling fluid to the anode is decreased and its temperature allowed to rise and vice versa. If desired, the sleeve may be fastened in position. 100

Referring to the form of our device shown in Fig. 2, a rectifier similar in all its general features to that of Fig. 1 is supplied with cooling fluid through a pipe 23. A tube 24 extends nearly to the end of the 105 anode and is not provided with a sleeve such as that shown in Fig. 1. A valve 25 is provided in the pipe 24 and a by-pass 26 is

connected around this valve and the cooling space of the anode, taking cooling fluid directly from the pipe 27 to the out-flow pipe 28. A valve 20 is inserted in the by-pass 5 26. By opening the valve 25 and closing the valve 29, the amount of cooling fluid passing through the anode may be increased with consequent lowering of its temperature with respect to the cathode and, conversely, 10 the closing of the valve 25 and the opening of the valve 29 will decrease the amount of cooling fluid passing through the anode and will cause its temperature to rise with respect to that of the cathode. 15 While we have shown our invention in two separate embodiments, we do not desire to have it restricted thereto but desire it to cover broadly any and all means whereby the amount of cooling fluid passing through 20 one electrode cooling space may be adjusted with respect to the amount of cooling fluid passing through another electrode cooling space.

Only such restrictions and limitations 25 should be placed upon our invention as are indicated in the appended claims.

We claim as our invention:

1. The combination with two heat-generating members, of means for maintaining 30 them at a predetermined difference of temperature comprising a source of cooling fluid, means for supplying cooling fluid from said source to a heat-radiating surface of one of said members, and means for supplying 35 a portion only of said cooling fluid to a heat-radiating surface of the other member.

2. The combination with two heat-generating members, of means for maintaining 40 them at a predetermined difference of temperature comprising a source of cooling fluid, means for supplying cooling fluid from said source to a heat-radiating surface of one of said members, means for supplying 45 a portion only of said cooling fluid to a heat-radiating surface of the other member, and means for varying the temperature difference between the two members by varying 50 the relative amounts of the cooling fluid supplied to the heat-radiating surfaces of the two members.

3. The combination with two heat-generating members, of means for maintaining 55 them at a predetermined difference of temperature comprising a source of cooling fluid, means for supplying cooling fluid from said source to a heat-radiating surface of one of said members, means for supplying a portion only of said cooling fluid to a heat-radiating surface of the other member, and 60 means for by-passing the remainder of said cooling fluid around the heat-radiating surface of the second member.

4. The combination with two heat-generating members, of means for maintaining 65 them at a predetermined difference of tem-

perature comprising a source of cooling fluid, means for supplying cooling fluid from said source to a heat-radiating surface of one of said members, means for supplying a portion only of said cooling fluid to a heat-radiating surface of the other member, means for by-passing the remainder of said cooling fluid around the heat-radiating surface of the second member, and means for varying the relative amounts of cooling fluid 70 passing over the heat radiating surface of the second member and through the by-pass thereto.

5. The combination with a vapor rectifier comprising an evacuated container having 80 a main anode and a cathode therein, of cooling means adjacent the cathode, cooling means adjacent the anode, means for passing a stream of cooling fluid through the cathode-cooling means, and means for passing 85 a portion only of said stream of cooling fluid through the active portion of the anode-cooling means.

6. The combination with a vapor rectifier comprising an evacuated container having a 90 main anode and a cathode therein, of cooling means adjacent the cathode, cooling means adjacent the anode, means for passing a stream of cooling fluid through the cathode-cooling means, and adjustable means for 95 passing a portion only of said stream of cooling fluid through the effective portion of the anode-cooling means.

7. The combination with a vapor rectifier comprising an evacuated container, a jacked 100 cathode and a hollow anode, a tube for supplying cooling fluid to the cathode jacket, a tube for conveying said cooling fluid from the cathode jacket to the interior of the anode, a baffle plate within the anode for 105 shielding the heat-dissipating surfaces thereof from a portion of said cooling fluid, and a tube for conveying the cooling fluid from the anode.

8. The combination with a vapor rectifier 110 comprising an evacuated container, a jacked cathode and a hollow anode, a tube for supplying cooling fluid to the cathode jacket, a tube for conveying said cooling fluid from the cathode jacket to the interior 115 of the anode, an adjustable baffle plate within the anode for shielding the heat-dissipating surfaces thereof from a portion of said cooling fluid, and a tube for conveying the cooling fluid from the anode.

9. The combination with an evacuated container, of a cathode therein, a cooling jacket surrounding the cathode, a hollow anode, a tube projecting into said hollow anode and terminating adjacent the end thereof, a peripheral baffle surrounding the end of said tube and extending into proximity to the end of the anode, and means for passing a stream of cooling fluid through the cathode and the anode, a portion of said stream be- 120 125 130

ing diverted from the hot surfaces of the anode by said baffle plate.

10. The combination with a vapor rectifier comprising an evacuated container, a 5 jacketed cathode, and a hollow anode, means for supplying cooling fluid to the cathode jacket, means for conveying the cooling fluid from the cathode jacket through the anode, and means for forcing part of the cooling 10 fluid to come into contact with the heat-radiating surface of the anode and for preventing the remaining part of the cooling fluid from coming in contact with the heat-radiating surface of the anode.

15. 11. The combination with a vapor rectifier comprising an evacuated container, a jacketed cathode, and a hollow anode, means for supplying cooling fluid to the cathode jacket, means for conveying the cooling fluid

from the cathode jacket through the anode, 20 means for forcing part of the cooling fluid to come into contact with the heat-radiating surface of the anode and for preventing the remaining part of the cooling fluid from coming in contact with the heat-radiating 25 surface of the anode, and means for adjusting the amount of cooling fluid forced into contact with the heat-generating surface of the anode.

In testimony whereof, we have hereunto 30 subscribed our names this 30th day of June, 1914.

GEORGE M. EATON,
SIDNEY W. FARNSWORTH.
